UNITED STATES PATENT OFFICE.

GEORGE ALLEN ROBERTS, OF PADUCAH, KENTUCKY.

CAR-ROOF.

SPECIFICATION forming part of Letters Patent No. 404,735, dated June 4, 1889.

Application filed August 25, 1888. Serial No. 283,807. (No model.)

To all whom it may concern:

Be it known that I, GEORGE ALLEN ROBERTS, a citizen of the United States, residing at Paducah, in the county of McCracken and State of Kentucky, have invented a new and useful Railroad Freight-Car Roof, of which the following is a specification.

My invention relates to improvement in freight-car roofs, in which are used single boards with metal pans under each joint of board.

The object of the invention is to provide a roof that is less expensive and at the same time more durable and effective than any other roof that has heretofore been provided. These objects are attained by the mechanism illustrated in the accompanying drawings.

Figure 1 of the drawings shows an end view of the roof as seen when standing at the end of car after the roof has been put on, the letter A representing the board, and B the metal pan. Fig. 2 represents metal pan as placed on roof, the lip of one panlapping into the other. Fig. 3 represents end view of pan. Fig. 4 represents a view of the roof, looking at the end of boards and pan at the eaves of roof, also shows how board and pan are connected. Fig. 5 represents a full view of the pan alone.

30 In all of the figures, the letter A represents the board, and the letter B represents the pan.

The boards forming this roof must be of a uniform width and thickness—say six inches wide and one and one-fourth of an inch thick. 35 The top side of board should be plain and smooth and the bottom side should be beveled. There should also be a saw-cut in bottom side of board to receive edge of pan, as shown in Fig. 4 of drawings. The pan is 40 formed by bending at right angles a strip of

tin, galvanized iron, or other metals, say three and one-half inches wide and turning up one-half inch on each edge. The pans must also be of a uniform width. One-half of the pans, or rather all the pans on one side of the 45 roof, are formed with a lip on one end for the purpose of bending down into the other pan (which has no lip) at the top or cone of roof. When the boards and pans are placed on roof and both fastened by nailing, there should be 50 a space of one-eighth of an inch between each two boards and over the center of the pans, in order to allow for swelling and shrinking of boards in wet or dry weather, also that there may be better ventilation to roof, enabling it to dry more rapidly, thereby preventing to a great extent the decay of roof. 55

I claim for the herein-described roof over all roofs cheapness and durability. It is cheaper in that it requires about one-third 60 less lumber of the same grade used in other wooden roofs and about one-half the labor to build it. It is more durable in that it is a single roof, and, as it will not hold the water, it is less liable to decay. 65

The above roof can be built with or without battening over joint or seams, as the builder prefers.

I claim—

In a roof, the combination of the boards 70 having their lower edges beveled away so as to form a chamber, with the pans B, having their edges turned up at right angles and made to fit in grooves formed in the under side of the boards, substantially as shown.

GEORGE ALLEN ROBERTS.
